UNITED STATES PATENT OFFICE.

FRANK H. BEYEA, OF AKRON, OHIO.

METHOD OF MANUFACTURING CABLE BEADS OR GROMMETS.

Application filed September 14, 1921: Serial No. 500,651.

To all whom it may concern:

Be it known that I, FRANK H. BEYEA, a citizen of the United States, residing at Akron, in the county of Summit and State of Ohio, have invented certain new and useful Improvements in Methods of Manufacturing Cable Beads or Grommets, of which the following is a specification.

This invention relates to the manufacture 10 of circular cables or grommets, such as used in the inextensible beads in pneumatic tires and it is the purpose of this invention to improve upon and simplify the manufacture of this article, over methods now in use.

15 In a prior application Serial No. 472,623 filed May 26, 1921, I have proposed to form the grommet from a circular central or core wire and an outer or covering wire distinct and separate therefrom. In the present application, however, I propose to use a single 20 wire for this purpose.

The method of my invention is illustrated by the drawings accompanying this application in which Fig. 1 is a view showing 25 the single piece of wire from which the circular cable is made.

Fig. 2 is a cross section on the line 2—2 of Fig. 1.

Fig. 3 is a side elevation of the bead cable 30 or grommet in the process of manufacture.

Fig. 4 is a side elevation of the completed grommet.

Fig. 5 is a cross section on the line 5—5 of Fig. 4.

35 The present application discloses a method of making a cable bead or grommet, which method is similar in some respects to the method disclosed in the prior application referred to above, in that the wire which comprises the bead is given a preliminary spiralling or crimping before the wrapping operation. The advantages of preliminarily crimping or spiralling the wire before wrapping it about itself to form the core wire, 40 are that when the spiralling is done as a preliminary operation and not during or as a part of the winding or wrapping operation, a more accurate and perfect spiral may be given to the wire and a higher carbon or 45 stiffer wire may be used for this purpose. Furthermore, the spiralling is done in a separate machine from the winding or wrapping machine, which simplifies the latter machine and reduces the liability of failures or disablement of the wrapping machine. Other objects and advantages will be

apparent from the description of the invention.

In my prior application above referred to, I proposed to use a separate core wire as a 60 foundation about which the outer or covering wire is wrapped. According to this invention however I propose to use the same wire as the core wire and cover it with a spiralled extension of itself. 65

Thus, in Fig. 1 the wire is shown pre-formed with the spiral or straight portion and prepared for the winding or wrapping operation. The wire is indicated as a whole by the numeral 1 and is formed with a 70 straight or unspiralled portion 2 and a spiralled or crimped portion 3. The straight portion 2 is of the proper size to form a complete core wire so that the ends of the straight portion will come to the point at 75 which the spiral begins, when the wire is bent around to form the core or foundation of the proper size for the finished grommet. The remaining portion of the wire is given a crimp or spiral of the proper pitch and 80 diameter so that when wound about the portion 2, it will closely cover the same.

My present process differs from those which have preceded it, in that the wire is given the spiral formation before it is assembled upon the carrier or spool or in the wrapping or winding machine. By Fig. 1, in which portions of the wire are broken, out, I have intended to show a length of wire sufficient to make a single complete bead core 90 or grommet, it being understood that the length of wire which goes into the machine will comprise a large number of units. 85

The wire for the beads, having been prepared in the manner shown with a number 95 of unit lengths, each composed of a straight portion 2 and a spiralled portion 3, is wound or assembled on a spool or carrier 4. The portion of the wire 2 is first run out and bent into the form of a circle with the end 100 of the wire against the first spiral. The spool 4 is then passed in an orbit about the portion 2 so that the portion 3 will wrap about the straight portion of the wire, the spool and the ring of wire moving in the 105 relative direction indicated by the arrow in Fig. 3. The wrapping operation is continued until the whole of the portion 2 of the wire is covered, which should run the wire out to the next succeeding straight portion. The 110 wire is then cut as at 5 in Fig. 4 so as to register approximately with the first end of the

- wire, although it may overlap slightly, if desired. The wire is then sealed or locked in place by any suitable means as shown at 6, which may represent a sleeve or clip or a soldered, brazed or welded joint. The wire cable is then stretched to bring it to the proper size and cause the spirals to lie together evenly and smoothly and is ready for incorporation in the bead structure.
- 10 In former practises it has been the custom to make wire beads by the use of a quill or die as a part of the bead which revolved about the core wire to give the spiral formation to the wire during the wrapping. Such
- 15 a practise has meant a setting of the machine in each winding operation so that the wire will run out straight for a portion or a whole of the core wire, and then resetting to give the wire the spiral formation. By preparing or performing the wire as shown and described I am enabled to dispense with the setting and resetting operations and as a result the manufacturer of the beads may be done with less labor and greater efficiency.
- 20 25 It will be noted that, as the wire is assembled upon the spool in crimped or spiralled form, it is necessary that the spool be passed around the wire in such fashion that the preformed spiral is not altered.
- 30 To do this the spool is maintained with its axis always perpendicular to the plane of the core. This method of winding is original with me and is covered generically in my prior applications, Serial No. 472,623
- 35 filed May 26, 1921, and Serial No. 499,305 filed September 8, 1921.

Changes and modifications may be made in the carrying out of the process of my inventions without departing from the spirit 40 thereof or sacrificing any of its benefits. The invention is not limited to the manufacture of endless bead wires but may be extended to other uses and relationships.

Claims:

- 45 1. A process of manufacturing circular cables or grommets, comprising forming a unit length of wire with a straight portion of sufficient length to form a core wire, and a spiralled portion of sufficient length to 50 cover the core wire, assembling the wire so shaped upon a carrier, drawing out the straight portion to form the core and then wrapping the spiralled portion about the said core until it is covered thereby.
- 55 2. A process of manufacturing circular cables or grommets, comprising forming a unit length of wire with a straight portion of sufficient length to form a core wire, and a spiralled portion of sufficient length to 60 cover the core wire, assembling the wire so shaped upon a carrier, drawing out the straight portion to form the core, wrapping the spiralled portion about the said core until it is covered thereby and uniting the end 65 of the wire to the body of the cable.

3. A process of manufacturing circular cables or grommets, comprising the steps of forming a wire with a straight portion and a spiralled portion, the straight portion being of a length sufficient to form the core 70 wire of the grommet and the spiralled portion being of a length sufficient to cover the core wire when wrapped around the same in a number of successive convolutions and then circling the straight portion to form 75 the core and wrapping the spiralled portion about the said core to cover the same.

4. A process of manufacturing circular cables or grommets, comprising the steps of forming a wire with a straight portion and 80 a spiralled portion, the straight portion being of a length sufficient to form the core wire of the grommet and the spiralled portions being of a length sufficient to cover the core wire when wrapped around the same 85 in a number of successive convolutions, then circling the straight portion to form the core, wrapping the spiralled portion about the said core to cover the same, and then uniting the end of the spiralled portion of 90 the wire to the body of the cable.

5. A process of manufacturing cables or grommets comprising the steps of forming a wire with straight portions and with spiralled portions in alternation, the straight 95 portion being of a length sufficient to form the core wire of the grommet and the spiralled portion being of a length sufficient to cover the core wire when wrapped about the same in a plurality of successive convolutions, 100 assembling the wire so shaped on a carrier, drawing from the carrier the straight length of wire and circling the same to form the core wire, then passing the carrier about the core wire until the spiralled portion of the 105 wire completely covers the core wire in a plurality of successive convolutions, then cutting the wire at the end of the spiralled portion.

6. A process of manufacturing cables or 110 grommets comprising the steps of forming a wire with straight portions and with spiralled portions in alternation, the straight portion being of a length sufficient to form the core wire of the grommet and the spiralled portion being of a length sufficient to 115 cover the core wire when wrapped about the same in a plurality of successive convolutions, assembling the wire so shaped on a carrier, drawing from the carrier the 120 straight length of wire and circling the same to form the core wire, then passing the carrier about the core wire until the spiralled portion of the wire completely covers the core wire in a plurality of successive convolutions, then cutting the wire at the end of the spiralled portion and securing the end of 125 the wire to the body of the cable.
